UNITED STATES PATENT OFFICE

CHARLES B. PENDLETON, OF LOS ANGELES, CALIFORNIA, ASSIGNOR TO CITIZENS NATIONAL TRUST & SAVINGS BANK, OF LOS ANGELES, CALIFORNIA, A NATIONAL BANKING ASSOCIATION OF THE UNITED STATES OF AMERICA

AUTOMATIC FLUID PRESSURE DISPLACEMENT PUMP

Application filed February 2, 1931. Serial No. 512,837.

This invention relates to means for elevating fluids. In my application for United States Letters Patent filed October 30, 1929, Serial No. 403,429, for means of elevating fluids, I have described a particular type of pump, of which the present invention is an improvement in certain aspects.

Pumps of the character described in said application function under ordinary circumstances in a very efficient manner but sometimes the pump at the bottom of the well sticks with the result that the pump will not operate efficiently and, in fact, will entirely stop operation. Unless an operator is present at the time that the pump ceases operation, the pump may remain idle in the well hole over a considerable period of time.

The present invention has for an object the provision of means whereby continuous operation of a pump of the character set forth in my copending application above referred to, is assured.

A further object of the invention is the provision of a pump incorporating all of the objects set forth in the copending application referred to.

Other objects include a pump which is simple of construction, inexpensive in cost of manufacture, and which produces superior results.

With the above and other objects in view, the invention consists in the novel and useful provision, formation, construction, association and relative arrangement of parts, members and features, all as set forth in the accompanying specification, shown in the drawing, and more particularly pointed out in the claims.

In the drawing:

10 Figure 1 is a longitudinal sectional view of a pump embodying the invention, the foot valve being in one position, and,

15 Figure 2 is a view similar to Figure 1, the foot valve being in a second position.

16 As a brief summary of the invention, it

may be said that I provide what is known as an expansion chamber member and within the chamber thereof I provide a foot valve. This foot valve is surrounded by a cage and the foot valve moves within the cage to allow entrance of oil into the expansion chamber or to close entrance of oil therein. Directly connected with the foot valve is a piston controlling entrance of gas under pressure within the expansion chamber, the arrangement being such that when the foot valve is open or raised from its seat the gas valve, which would be the piston associated with the foot valve, is closed; and when the foot valve is closed to its seat, the gas valve is open. The cage that surrounds the foot valve and the gas valve are thought to be novel, in that a portion of the gas under pressure is capable of passing through the gas valve to a zone surrounding the top of the foot valve. The presence of gas around the foot valve despite the normal closing of the gas valve, is such as to "blow a bubble" and force oil from above the foot valve. To this end, ports are provided at a portion of the cage through which oil and a portion of the gas may escape. Thus, when the foot valve moves upwardly to allow oil to enter the expansion chamber, gas will constantly keep above the foot valve, to the end that if any deleterious substance should in any manner get within the gas valve, to-wit, between the piston and its cylinder, to hold it against movement, gas pressure is gradually built up against the top surface of the foot valve sufficient to force the foot valve downwardly and thus assure that the pump will at all times operate. By way of brief explanation, it may be said that a separate line is provided for causing gas under pressure to be directed into the expansion chamber, and that a separate tubing is used through which the oil is raised. The oil enters the expansion chamber when the foot valve is open and the gas valve closed and the oil will enter the tubing provided

50 55 60 65 70 75 80 85 90 95

for it and rise until it has reached what is known as its static level, whereupon the foot valve is adapted to close under influence of gravity under normal conditions. Gas then 5 enters the expansion chamber to provide a gas sludge or piston for the purpose of lifting the oil (without emulsifying it) beyond its static level. After the oil has been lifted, the foot valve opens and the gas valve closes 10 until more oil has entered the expansion chamber and reached its static level within the tubing, whereupon the sequence of operation is repeated. Almost all oil contains grit, such as sand and the like, and this grit 15 if it contacts with the surface of the gas valve, is liable to stop operation of the valve. Hence, I have provided a petticoat type of cage surrounding the gas valve and ports that communicate therewith. Normally, gas 20 will pass through these ports in sufficient amount to "blow a bubble" and which bubble will prevent oil from entering the petticoat and thus prevent sand from contacting with the gas valve. However, even this precaution 25 is not fool-proof. Consequently, by providing a seepage of gas past the gas valve and above the foot valve, I have provided a method whereby sticking of the gas valve is efficiently overcome in the manner just stated. 30 Referring with particularity to the drawing, I have shown a casing 1 which leads to the surface of the well hole and which casing communicates with a source of gas under pressure. In certain aspects of the invention, 35 this casing may likewise communicate with a source of liquid, such as oil, to be used in priming the pump. This casing will extend downwardly within the well hole adjacent the oil sands as is usual practice. At 2, I have 40 shown tubing, and packing 3 of some form is interposed between the casing 1 and said tubing. It is intended that oil from the oil sands should pass through the tubing 2. This tubing in turn is directly associated with a 45 coupling 4 ordinarily known as a reducer coupling. The portion of largest diameter of said coupling lies above the packing 3 and is adapted to be secured to a casing 5 forming an element of the expansion chamber member. It may be said that this casing has ends 50 of reduced diameter, as shown at 6 and 7, in the present instance, the end 6 being screw-threaded to the coupling 4 and the end 7 screw-threaded to coupling 8. The coupling 55 8 is provided with a central internal gas inlet line 9 having branches 10 and 11 communicating exteriorly of the said coupling. Furthermore, the said coupling 8 is externally screw-threaded at 12 and shouldered at 13, 60 whereby the end of a screen 14 may be secured thereto. This screen may extend upwardly for a given distance within the casing 1 and then bent inwardly for engagement with the periphery of tubing (not shown) and secured 65 to the coupling and communicating with the

interior of the coupling and particularly that portion marked 15. In other words, the tubing communicates with the interior of the expansion chamber member, to-wit, the interior of the casing 5. The fluid pressure displacement pump includes as its elements, taken generally and as a group, a gas inlet valve 16, a liquid inlet valve, also termed foot valve, 17, and the displacement chamber heretofore referred to. This displacement chamber, as 75 stated, includes the casing 5 and that area within the casing surrounding the gas inlet valve and the foot valve or liquid inlet valve. 80

The gas inlet valve includes a cylinder or housing 18 externally screw-threaded at 19 for threaded engagement with threads 20 of the central internal gas inlet line 9. This cylinder is externally shouldered at 21 and the cylinder is transversely bored to provide ports 22 below the shouldered portion. Adapted to be carried on said shoulder and to spacedly surround the cylinder at the zone of the ports and beyond said ports is an annular skirting 23. This construction provides an annular space 24 between the periphery of a portion of the cylinder or housing and the interior of the skirting, and which space is in direct communication with the interior of the expansion chamber member and with said ports 22. Forming a further element of the gas inlet valve is a piston valve 25 adapted for reciprocation within the cylinder or housing 18. It is perhaps superfluous to state that the cylinder would include the cylindrical bore 26, within which the piston moves. This piston includes the so-called piston head 27 and stem 28 secured to the head. The head has a reduced diameter extension 29 and this extension is formed with a transverse port 30 and the piston head is formed with a longitudinal bore 31 communicating with the transverse port 30. One or more bores 32 communicate with the bore 31 and with the base 33 of the piston head. The bores 31 and 32, of course, constitute ducts and the bores 32 are at an angle relative to the central bore 31 for the obvious reason that the piston stem must be avoided in order that there be a gas passage-way through said piston head. Obviously, any other construction must be resorted to, such as by boring the piston eccentrically from base to top. 100

The foot or liquid inlet valve 17 is adapted to be confined and operate within a cage 34. This cage, in the present instance, is integrally connected with the cylinder or housing 18. The size of the cage will of necessity depend upon the size of the foot valve and, in the present instance, the cage has an enlarged internal and external diameter relative to the size of the cylinder 18. 110

The cage is screw-threaded at 35 for engagement with a seat member 36. This seat member is formed with an external annular flange 37. An annular locking nut 38 is se- 120

cured to internal threads 39 of the expansion chamber casing 5, and this locking nut is adapted to bear against annular packing 40 lying between the flange 37 and a portion 5 of the periphery of the seat member 36. The construction is such that any liquid passing through the pump tubing 2 will be received within the reducer coupling 4 and must pass upwardly through the annular nut, the annular seat and into the cage. This cage is formed with one or more transverse ports or openings 41 and these openings are above the normal position assumed by the seat member when screw-threaded to the cage. 10

15 The crown 42 of the cage is formed with a central depending boss 43, and said crown is likewise provided with a central bore 44. This bore communicates between the interior of the cage and the bore 26 of the cylinder. 20

25 Adjacent the inner surface of the crown and transversely within the side wall of the cage, are one or more ports 45. These ports are positioned above the plane of the end of the boss 43. The end 46 of the boss is likewise provided with a surface groove 47. The stem 28 secured to the piston head, passes through the bore 44 and is secured to the foot valve 17. This foot valve includes a body 48 provided with a conical-shaped head 49, and with a 30 flange 50 extending beyond the periphery of the portion 51 of the body. The top surface of the body is formed with an annular depression or concavity surrounding the stem 28, as shown at 52. The bore 44 through 35 the crown of the cage has a slight "tolerance," that is to say, is slightly greater as to diameter than the diameter of the stem 28.

The operation, uses and advantages of the invention are as follows:

40 While I have set forth at the beginning of this specification a brief statement of the operation and function to be performed by my said invention, I may add additional remarks. The pump may have to be primed by 45 directing a liquid downwardly within the casing 1, and which liquid would pass through the screen 14 and into the ducts 10 and 11 against the piston. If the foot valve is closed against its seat, as shown in Figure 50 2, this fluid would in turn pass through the ports 22 of the cylinder and outwardly through the annular space 24 between the periphery of the cylinder and the skirt 22, and into the expansion chamber, thence upwardly to the surface of the well, it being 55 remembered that the portion 15 of the coupling communicates with pump tubing. Ordinarily, the pump is immersed in the oil within the well hole, to the end that the oil 60 would rise or normally be within the pump tubing up to a certain distance, to-wit, its static level. The precise depth to which this oil ordinarily rises within the pump tubing would be determined by the engineer. Quite obviously, after the pump has been primed

and the foot valve opened, gas under pressure directed downwardly into the annular space included between the pump tubing (not shown) and the interior of the casing 1, will enter through the perforations 14, the ducts 10 and 11, and be directed against the piston 25. Until the oil to be raised has reached its static level, the foot valve ordinarily will remain open. However, when the oil has reached its static level, the foot valve ordinarily will drop under influence of gravity and seat, at which time further flow of oil upwardly from the pump tubing 2 into the cage is stopped. The piston 25 then is moved so as to open communication from the cylinder through the ports 22 into the expansion chamber. The gas will expand until a sufficient amount has been received therein to act as a gas sludge and lift the oil thereabove, whereupon after the pressures begin to equalize, the foot valve will automatically open and gas flow will be stopped by the piston moving upwardly and closing the ports 22 and further oil will enter through the tubing 22 through the ports 41 of the cage, into the expansion chamber, and upwardly within tubing connected with portion 15 of the coupling until said oil reaches its static level, whereupon the sequence of operation will be repeated.

As stated, almost all oil contains some grit, such as sand, and often this sand or grit will be received within the cylinder, with the result that the piston will be wedged against movement within the cylinder. If this occurs, the pump will, of course, cease to operate or, at best, only operate intermittently when the grit is dislodged. An object of this invention is to overcome any interference with the proper working of the foot valve and the gas intake valve. It will be noted that ports are provided in the piston, as shown at 30, 31 and 32. Therefore, a portion of the gas directed downwardly between the casing 1 and the pump tubing and passed through the screen will likewise be received behind the piston. This gas will also pass between the stem 28 and the bore 44. As the top surface of the foot valve is formed with a slight concavity or depression 52, the gas may be received in said concavity. Thus, the gas may pass through the surface groove 46 into the space included between the crown and the top surface of the foot valve. Ordinarily there would be a tight fit between the top surface of the foot valve and the face of the boss, but this construction will permit escapage of gas between said surfaces. This gas will be received within, as stated, the space included between the top surface of the foot valve and the interior of the crown. Also, the gas may escape through the ports 45.

Before stating further the operation, and

assuming that the pump is operating properly, the ports 30, 31 and 32 of the piston allow for escape of gas behind the piston when the piston moves downwardly within the cylinder and the foot valve closes to its seat. Therefore, these ports act to perform a dual function. There is a difference in area between the piston and the foot valve. Thus, under normal circumstances, the foot valve will be raised by the incoming oil which is seeking its static level and against gas pressure. If the oil has reached its static level, and assuming that grit may have been received between the cylinder and piston, the piston tends to stick and the foot valve to remain either entirely open or partly open. The gas, however, will move downwardly through the ports in the piston between the stem and the bore 44 and upwardly through the concavity and surface groove in the foot valve and boss, respectively, and be received in the space between the foot valve and the crown. This gas will exert a pressure against any fluid that is received within the crown and particularly in the space just mentioned, with the result that the oil will be forced downwardly from above the foot valve. Hence, a gas pressure is exerted at this zone and this gas pressure will gradually build up to such an extent that the pressure of the oil against the foot valve is overcome and likewise the piston is moved irrespective of what may normally be holding it against movement within its cylinder. In other words, what may be termed "blowing a bubble" actually occurs. This bubble is, of course, a gas bubble against the oil. In actual practice, this bubble is at all times being blown for the reason that gas will be passing into the space included between the top of the foot valve and the crown. It is true that the amount of gas escaping at this zone is relatively small but it is sufficient for the purpose intended.

45 The function of the petticoat has been described in my copending application referred to.

It will be noted that the bore of the cylinder is enlarged at 53. This provided a slight expansion chamber and furthermore a space within which grit may be received without necessarily blocking operation of the piston. It will be apparent that oil will not find its way upwardly between the piston stem and the bore 44, due to the constant presence of gas under pressure, which forces it outwardly. I have found that the pump constructed in accordance with this invention functions perfectly.

60 I do not wish to confine my invention to any particular form of clearance between the piston and the stem, as I may within the scope of the invention provide a small port in the crown extending to the space that would normally be between the crown and

the top of the foot valve, the principle of the invention being to permit of reception of gas in small amounts above the foot valve for the purpose of forcing the foot valve downwardly in case the piston should stick. 70

It is obvious that various changes and modifications and variations may be resorted to in departure from the particular showing of the drawing without departing from the true spirit thereof. 75

I claim:

1. In a device of the character disclosed, an expansion chamber member, a gas valve and a foot valve for controlling liquid passage inter-connected for joint operation, a cage for the foot valve, means for admitting gas into the expansion chamber when the gas valve is opened, the foot valve closing entrance into the expansion chamber, and means whereby gas is at all times directed above said foot valve. 80

2. In a device of the character disclosed, a foot valve, a cage therefor, said foot valve normally controlling entrance of liquid within said cage, and means for directing a gas between the foot valve and the cage. 90

3. In a device of the character disclosed, a cage, a foot valve adapted for movement within said cage and to control entrance and exit into and from said cage of a liquid, and means for directing a gas between the foot valve and the top of the cage to thereby exert a gas pressure at all times against the foot valve. 95

4. In a device of the character disclosed, a valve, a cage therefor valve controlling the entrance and exit of a liquid into and from said cage, and means for directing a gas to a zone included between the valve and the cage, to thereby exert a gas pressure against said valve and normally urge it to seat; an expansion chamber member surrounding the cage and communicating therewith, said cage being formed with port openings through which said gas may pass into the expansion chamber member. 100

5. In a device of the character disclosed, a gas valve, a foot valve, a stem between said valves, a cage within which said foot valve is adapted to move said foot valve controlling entrance of a liquid therein; a cylinder for said gas valve, and means for directing a gas to said gas valve, said gas valve being provided with a by-pass port and whereby gas may pass through said gas valve into a zone above the foot valve, said cage being formed to allow a gradual escape of gas between the foot valve and the cage and thereby build up a gas pressure against the foot valve, in combination with an expansion chamber member surrounding the cage and cylinder, and within which liquid is received when the foot valve is opened, the gas valve being closed, and within which expansion chamber member gas is directly admitted when the 110 115 120 125 130

foot valve is closed, the gas valve being open.

6. In a device of the character disclosed, a valve, a cage therefor, said valve controlling entrance and exit of a liquid into and from said cage, and means for directing a gas to a zone included between the valve and the cage to thereby exert a gas pressure against said valve to at all times urge it to seat.

5
10 In testimony whereof, I have signed my name to this specification at Los Angeles, California, this 17th day of January, 1931.

CHARLES B. PENDLETON.
